Franklin & Marshall
ATTORNEY

UNITED STATES PATENT OFFICE.

WILLIAM W. MILLER, OF NEW YORK, N. Y., ASSIGNOR TO THE CUTLER-HAMMER MFG. CO., OF MILWAUKEE, WISCONSIN, A CORPORATION OF WISCONSIN.

RESISTANCE.

Application filed February 13, 1923. Serial No. 536,052.

To all whom it may concern:

Be it known that I, WILLIAM W. MILLER, a citizen of the United States, residing at New York, in the county of Bronx and State of New York, have invented new and useful Improvements in Resistances, of which the following is a full, clear, concise, and exact description, reference being had to the accompanying drawing, forming a part of this specification.

This invention relates to resistances, and more particularly to the mounting and terminal arrangement of resistance elements having insulating bases with which the resistor is associated by winding or otherwise.

In the construction and assembly of such resistance elements great difficulty has heretofore been experienced in providing for support and mounting thereof with adequate ruggedness and resilience to insure permanence of the installation, and the present invention has among its objects that of overcoming such difficulty.

Another object is that of providing combined supporting and terminal means for such resistance elements enabling stacking thereof in a manner to simulate that of the ordinary grid resistance.

Another object is that of providing for such resistance elements, detachable supporting terminals providing for rugged and reliable mounting of the elements in different desired relations.

Another object is that of providing a resistance unit having supporting terminals which may be adjusted with reference to the resistance element or elements to provide for arrangement of the latter in different relation with reference to other units and to the source of energization.

Another object is that of providing an exceedingly simple, rugged and durable supporting terminal device which may be readily applied and rearranged with respect to a resistance element to provide for use of the latter in different relations.

Other objects and advantages will hereinafter appear.

In the accompanying drawing wherein is illustrated an embodiment of the invention;

Fig. 1 is a front elevational view showing a given relation of a pair of resistance elements embodying the present invention.

Fig. 2 is a side elevational view of the same;

Fig. 3 is a view similar to Fig. 1 but illustrating the resistance elements in different relation; while

Fig. 4 is a side elevational view of the resistance elements arranged as in Fig. 3.

Referring to Fig. 1, the same illustrates a pair of resistance elements of conventional form, each being provided at its ends with supporting terminal devices more fully described hereinafter, said devices being arranged in a particular manner to provide for support of said elements in a particular manner and to facilitate connection of the elements electrically in parallel relation to one another.

The resistance elements illustrated may be of practically any standard type, each preferably comprising an insulating base 5 having a resistor 6 wound thereon, a coating 7 of enamel or other insulating material being preferably applied and permanently secured about the base and the resistor as by adhesion. The resistor is provided at its ends with projecting terminal portions such as the portion 8 illustrated.

The herein contemplated supporting terminal devices for the aforescribed element preferably comprise a pair of metallic or other conductive strips 9 secured respectively to the end portions of the base 5 of the element substantially as illustrated.

In practice the members 9 may comprise castings, punchings, stampings or the like each being shaped to correspond with the analogous terminal portion of a grid resistor and comprising an elongated lug or shank 10 of such thickness as to afford ample mechanical strength with a given amount of flexibility or resiliency, and preferably of a length somewhat less than the width of the base to which it is attached.

Each member 9 is further provided with an enlarged portion 11 extending a material distance beyond the adjacent side of the resistance element and also offset laterally to extend a considerable distance outwardly beyond the adjacent end of its associated base. The portion 11 is furthermore enlarged in the direction of greatest length of its associated base, the enlarged portion being provided with a relatively large opening 12 to receive the usual mounting rod or bar. Further the portions of the member 9 adjacent said opening 12 may be

made of materially increased thickness rel-

ative to that of the remaining portions of said member thereby affording ample mechanical strength and material for electrical conductivity to this portion of the member.

5 Further, the extension 10 of each of said members 9 is provided with a plurality of screw threaded openings 13 adapted to register with corresponding openings in the corresponding portions of the base 5, thereby providing for securement of the latter to the former by means such as the screw 14 and bolt 15 illustrated. In practice the terminal portions 8 of resistor 6 are preferably bent about and clamped by the bolts 15 substantially as illustrated, whereby the members 9 are adapted to serve as terminals for the resistor. It is of course, to be understood that other securing means may be substituted for those described, if desired.

20 As illustrated particularly in Fig. 1, the members 9 are secured to the opposite ends but preferably upon the same side of the individual resistance elements, and each is arranged to project from the same edge of the individual element, thereby providing for two point suspension of the assembled unit by means of rods or bars in the usual manner while also facilitating connection of the individual elements in parallel relation to one another electrically.

25 Again referring particularly to Fig. 2, it is apparent that the thickness for stacking of the assembled unit is minimized and is not materially in excess of that of a grid resistor of corresponding general dimensions.

30 Referring now to Figs. 3 and 4 of the drawing the resistance units and also the supporting terminals therefor are in all respects similar to those aforescribed. However, the relation of the supporting terminals to the individual units has been changed to provide for three point rather than two point suspension of the resistance units when mounted in groups of two upon supporting rods. Also connection of the resistance elements in series relation is facilitated.

35 The specific difference in arrangement consists in assembling the supports upon the base to project from opposite edges thereof rather than from the same edge as in the previous construction and here again by reference to Fig. 4 it is apparent that the thickness of the assembled group of elements does not materially exceed twice the thickness of the conductive material surrounding the opening 12.

40 It is of course apparent that if desired the portions 11 of the members 9 may be interrupted to provide for assembly of the unit laterally upon its supporting rod. Also in certain cases it may be desirable to effect integral construction of those elements 9 which when assembled would register with one another. Further it is of course obvious

45 that the units illustrated in Fig. 1 may, if desired, be connected electrically in series relation to one another through interposition of suitable spacers between the adjacent members 9 of said units, the spacer located 70 between the members 9 at one end of each pair of units being conductive and the spacer between the said members located at the opposite end of such pair of units being insulating in character.

50 By the foregoing construction and arrangement it is apparent that exceedingly simple, durable and effective terminal supporting means for a resistance element is provided, whereas the aforescribed functional flexibility provides for adaptation of the resistance elements to mounting in groups or units and in different arrangements, including those particularly described.

55 What I claim as new and desire to secure by Letters Patent is:

1. The combination with a resistance element comprising an insulating base and an associated resistor, of supporting means therefor comprising a grid resistance terminal.

2. The combination with a resistance element comprising an insulating base and a resistor, of combined supporting and terminal means for said element comprising similar conductive members each having a part to be secured to an end portion of said base and a portion for mounting directly upon a support, and securing means providing for clamping of said members individually to said base in different relations and also providing for electrical connection of said members to said resistor.

3. The combination with a resistance element, comprising an insulating base and a resistor associated therewith, of detachable supporting and terminal means for said element enabling arrangement of a plurality of such elements in pairs in different relations to simulate the stacking arrangement of ordinary grid resistors.

4. The combination with a pair of resistance elements each comprising an insulating base and an associated resistor, of detachable supporting and terminal means for said elements to be secured thereto in different relations optionally for enabling arrangement of said pair of elements as a unit to simulate the stacking arrangement of either the two point suspension or the three point suspension resistance grid.

5. The combination with a pair of resistance elements each comprising an insulating base and an associated resistor, of detachable conductive supporting terminal devices, each shaped to correspond with a terminal portion of an ordinary grid resistor, to be secured to the remote end portions of the individual resistance elements in different

relations optionally for enabling stacking of said elements as a unit to simulate the stacking of an ordinary grid resistance.

6. The combination with a pair of resistance elements each comprising an insulating base and an associated resistor, of terminal means providing for assembly and

support of said elements as a unit, comprising a plurality of opposed and interfitting grid resistance terminals.

In witness whereof, I have hereunto subscribed my name.

WILLIAM W. MILLER.
